UNITED STATES PATENT OFFICE.

URBAN A. KREIDLER, OF DAYTON, OHIO, ASSIGNOR TO McLAREN-CONSOLIDATED CONE CORPORATION, OF DAYTON, OHIO, A CORPORATION OF DELAWARE.

DESIGN FOR AN ICE-CREAM CONE.

Application filed January 12, 1928. Serial No. 24,833. Term of patent 14 years.

To all whom it may concern:

Be it known that I, URBAN A. KREIDLER, a citizen of the United States, residing at Dayton, Montgomery County, Ohio, have invented a new, original, and ornamental Design for an Ice-Cream Cone, of which the following is a specification, reference being had to the accompanying drawing, forming part thereof.

Fig. 1 is a side elevation of an ice cream cone showing my new design, the opposite side of the cone being the same as that illustrated.

Fig. 2 is a cross sectional view on the line 2—2 of Fig. 1.

I claim:

The ornamental design for an ice cream cone substantially as shown.

URBAN A. KREIDLER.
